HIS ATTORNEY

UNITED STATES PATENT OFFICE.

HARRY H. HARNSBERGER, OF NEW YORK, N. Y.

CIGARETTE HOLDER.

1,359,803.

Specification of Letters Patent. Patented Nov. 23, 1920.

Application filed April 5, 1919, Serial No. 287,717. Renewed October 15, 1920. Serial No. 417,277.

To all whom it may concern:

Be it known that I, HARRY H. HARNSBERGER, a citizen of the United States, residing at Brooklyn, in the county of Kings and State of New York, have invented certain new and useful Improvements in Cigarette-Holders, of which the following is a specification.

This invention relates to articles generally known as cigar or cigarette holders, and it has for its object to provide the holder with relatively inexpensive, compact, easily operated and efficient devices whereby the spent end or so-called stump of the cigar or cigarette may be conveniently ejected from the holder. A further object of the invention is to adapt the ejecting devices to inexpensive application to holders of the size, shape and material now in general and public use, without defacing them or materially adding to their bulk or shape. Additional advantages and utilities of the invention will appear from the detailed description below.

In the drawings Figure 1 is a longitudinal sectional view of a holder embodying my invention; Fig. 2 is a view similar to Fig. 1, embodying a modified construction; Fig. 3 is a view somewhat enlarged of the forward end of a holder embodying a still further modification; Fig. 4 is a vertical sectional view taken on the line 4—4 of Fig. 1, looking in the direction of the arrows; Fig. 5 is a vertical sectional view taken on the line 5—5 of Fig. 3, looking in the direction of the arrows.

1 represents the body of the holder. It may be made of ordinary construction and of any suitable material. It is provided with a central longitudinal bore or draft passage 2, which connects at its forward end with an enlarged bore or recess 3, which receives the end of the cigar or cigarette. 4 represents a recess cut in the side of the body part but which does not extend so far inwardly as to open into the draft bore 2, and it is of a length sufficient to permit the necessary longitudinal movement of the ejector and its associated parts about to be described. 5 is a channel or passageway cut through the body part 1 and connecting the recess 4 with the recess 3. The ejector comprises the following parts, see best Fig. 3. 6 is a stiff rod, preferably of metal, which is adapted to slide longitudinally through the bore 5. It extends through the

recess or chamber 4 and projects forwardly into the inner end of the recess 3. The forward end of this rod is turned downwardly at substantially right angles and bent into substantially circular form to produce an eye 7 to act as a push plate for the ejection of the cigar or cigarette stump. The eye, having an opening in its center part, will not interfere with the draft during the smoking operation. The inner end of the rod 6, as shown in Fig. 1, may be turned upwardly, as at 8, and passed through and riveted, or be otherwise attached, to a sliding plate 9, which acts as a cover plate for the recess 4 and as a push plate, whereby the ejector may be projected and retracted. The upper surface of this plate may beneficially be roughened or knurled to aid in these operations.

10 is a spring, which encircling the ejector rod 6, abuts at one end against the forward end of the recess 4 and at the other end against any suitable abutment on the rod 6, as, for example, the rectangular portion 8 of that rod. The function of the spring is to retract the ejector 6 when released from the forward pressure of the thumb of the operator, thus returning the parts to normal or primary position.

Inasmuch as this automatic spring action, while a convenience, is not at all essential, and in some instances might be found objectionable, I illustrate in Fig. 2 a modified form of the invention, in which the spring 8 has been eliminated, and in this construction also I modify the other parts as follows:

Instead of the ejector rod 6 being bent at right angles for connection with the cover plate 9, I provide a downwardly extending stud 11 on the plate with which the push rod 6 engages. This engagement may be by threading the rod to the stud, as shown in Fig. 2, or by splitting the lug as shown in Fig. 5, thus forming upon it two resilient prongs or parts 12, 12, between which the end of the push rod 6 may be forced by pressure, so that the pinch of the resilient parts 12, 12, will hold the push rod in position. In this construction also I show a further modification, that is to say, instead of bending the forward end of the ejector rod within the cigar or cigarette holding recess 3 at right angles and forming it into an eye or loop, I may flatten the end of that rod, as by the stroke of a ham-

mer, and then bend the flattened or plate-like part at right angles, as shown in Fig. 3, and in the center of this flattened part I punch an opening 13, through which the draft may pass to the draft bore 2, as indicated.

The operation is as follows: The appropriate end of the cigar or cigarette is inserted into the recess 3 in its forward end 10 in the usual manner, and being lighted the smoking proceeds until the cigar or cigarette has been consumed, or it is otherwise desired to eject the stump or partly consumed article, whereupon the ejector or 15 cover plate 9 is pushed forwardly by the thumb of the operator which will carry the looped or flattened end of the ejector against the inner end of the cigar or cigarette stump, and slight pressure being applied, the same 20 will be ejected from the recess 3, whereupon the operator discontinuing the forward pressure of his thumb, the spring 10, if present, will automatically cause the retraction of 25 the ejector and of the cover plate 9; but if the spring be not employed, then the mere backward movement of the operator's thumb will effect the same movements of these parts, thus returning the holder to primary 30 condition, ready for a second use.

It will be noted that the cover plate 9 is of such length and width as that it may entirely cover and hide the recess 4, thus preventing the entrance of dirt or other matter 35 and presenting a smooth, handsome appearance, rather ornamental than otherwise, upon the exterior of the holder. It will be further noted that inasmuch as when the ejector is projected, its forward end extends beyond the holder proper, as illustrated in 40 dotted lines on Figs. 1 and 2, that it will be easy by the employment of suitable tools, either to thread the ejector rod 6 into the lug 11, or other appropriate part of the cover plate, or to otherwise effect suitable 45 engagement between these parts.

It will be obvious to those who are familiar with such matters that various modifications may be made in the details of construction without departing from the essentials of the invention. I therefore do not limit myself to the details described and 50 illustrated.

I claim:

1. A holder having in addition to an inte-

gral body part provided with a longitudinally extending draft passage and enlarged recess at its forward end, the following additional devices: an elongated cavity in one side of the body part parallel to the draft passage, a channel connecting the forward end of the cavity with the rearward end of the enlarged recess, and an ejector rod movably extending through said channel and operable from the outside of the holder through said cavity and having its forward end formed into a perforated ejector plate or part. 55

2. A holder having in addition to an integral body part provided with a longitudinally extending draft passage and enlarged recess at its forward end, the following additional devices: an elongated cavity in one side of the body part parallel to the draft passage, a channel connecting the forward end of the cavity with the rearward end of the enlarged recess, a longitudinally movable cover plate for the cavity, an ejector rod movably extending through said channel and attached to the cover plate within said cavity and having its forward end formed 60 into a perforated ejector plate or part, and a retractile spring within said cavity adapted to automatically return the parts to their primary position. 70

3. A holder having in addition to an integral body part provided with a longitudinally extending draft passage and enlarged recess at its forward end, the following additional devices: an elongated cavity in one side of the body part parallel to the draft passage, a channel connecting the forward end of the cavity with the rearward end of the enlarged recess, a longitudinally movable cover plate for the cavity of such length and width as to cover the same in 90 all positions of the ejector, and an ejector rod movably extending through said channel and attached to the cover plate within said cavity and having its forward end formed into a perforated ejector plate or 95 part. 100

In testimony whereof I affix my signature in presence of two witnesses.

HARRY H. HARNSBERGER. [L. S.]
